UNITED STATES PATENT OFFICE.

VINCENT CHELENA, OF ATLANTA, GEORGIA.

CHECK MARKING AND PROTECTING DEVICE.

Application filed June 7, 1922. Serial No. 566,669.

To all whom it may concern:

Be it known that I, VINCENT CHELENA, a citizen of the United States of America, residing at Atlanta, in the county of Fulton and State of Georgia, have invented certain new and useful Improvements in Check Marking and Protecting Devices; and I do hereby declare that the following is a full, clear, concise, and exact description of the invention, such as will enable others skilled in the art to which it appertains to make and use the same.

This invention relates to improvements in check marking and protecting devices, having for an object to provide a portable check marking and protecting device provided with a novel form of paper engaging and marking roller, the same carrying circumferentially arranged teeth thereon so shaped as to form series of projections upon the several sides of a check or similar instrument marked thereby, those portions forming such projections being torn or rather pulled free from the body and thereby rendered absorbent, thus enabling a person examining the check to readily ascertain whether it has been altered from its original form, subsequently to the marking thereof.

It is likewise an object of the invention to provide the device with a frame for supporting the marking roller whereby when the same is moved in one direction the marking teeth will be permitted to engage and form series of projections upon a check, but when moved in the opposite direction, to cause such roller to move in its innermost position, whereat the marking teeth will be prevented from engaging the check, thus ensuring the forming of the proper markings thereon.

Yet another object of the invention is to provide a frame having an extension on one end thereof which is adapted to be bent upon itself over the outer side of the marking roller to afford an effectual guard or shield for the same.

Other objects will be in part obvious and in part pointed out hereinafter.

In order that the invention and its mode of operation may be readily understood by persons skilled in the art, I have in the accompanying illustrative drawings and in the detailed following description based thereon set out one possible embodiment of the same:

In these drawings:

Figure 1 is a side elevation of the im-

proved device showing the manner in which the projections are formed upon the face side of a check or similar instrument, which as will be understood, is formed of paper or similar material;

Figure 2 is an end elevation of the improved marking roller;

Figure 3 is a side elevation of the same;

Figure 4 is a plan view of the frame blank; and,

Figure 5 is a fragmentary detail in vertical longitudinal section through a check or like instrument marked with the device showing the outer portions of the projections torn from the body of the sheet.

Having more particular reference to the drawings, in connection with which like characters of reference will designate corresponding parts throughout the improved device may be stated to consist of a frame formed of a strip of sheet metal, the body of the frame being indicated by the numeral 1 and having one of the end portions thereof curved upon itself to provide a spring clasp 2 adapted to be snugly engaged about a pencil or pen or similar device. Laterally disposed wings 3 are formed upon the intermediate portion of the sides of the body 1 at opposite points and are bent at substantially right angles thereto as shown in the Figure 1, having right angular bearing slots 4 formed therein for rotatably supporting the marking roll, hereinafter more fully described. The intermediate portion of the body 1 is cut away as at 5 to provide an opening for receiving the inner portion of the marking roll together with the marking teeth therethrough, in order that such teeth may be engaged with a check or similar instrument 6, which latter, as will be understood is formed of paper or similarly fragile sheet material.

Disposed transversely of the body 1 is a cylindrical marking roller 7 having the opposite ends of a supporting shaft 9 extended from the corresponding ends of the same and loosely mounted in the right angularly formed bearing slots 4 in the side or supporting wings 3. By reason of the positioning of the marking roll 7, it will be noted that the inner portion thereof will be permitted to extend partially through the opening 5, for a purpose which will be presently apparent.

A series of equi-spaced marking teeth are

arranged upon the peripheral surface of the cylindrical marking roller 7, as shown in the Figures 2 and 3 and are adapted to be passed through the opening 5 in the intermediate 5 portion of the body 1 into engagement with the check or similar sheet 6. These marking teeth 8, as will be noted, are tangentially disposed with relation to the peripheral surface of the marking roll and are of substantially triangular shaped formation, having the outer portions of certain of the sides thereof angularly cut or formed as indicated at 10, whereby they will more readily enter and penetrate the check or sheet of material 15 6 to be marked therewith. In this connection, upon reference to the Figure 1, it will be seen that with movement of the frame of the device in the direction indicated by the arrow, the tangential sides of the marking 20 teeth 8 will flushly engage the adjacent sides of the check or sheet 6 during rotation of the marking roller and with continued movement of the device, such teeth will be caused to enter and penetrate the sheet, thus forming 25 a series of indentations therein, which indentations, of course, form projections upon the several sides of the sheet which constitute the face and reverse side thereof, the former receiving the writing or descriptive matter. Because of the pointed free 30 ends of the triangular marking teeth, the outer portions or tips of these projections will be torn or broken away from the body of the check or sheet 6 as clearly shown in 35 the exaggerated illustration offered by the Figure 1, such tearing or breaking away of the outer portions of the projections, rupturing the fibers of the paper or other material of which the sheet is composed and 40 thereby rendering the same absorbent.

An extension 11 is formed upon that side of the body 1 opposite the curved attaching slip 2 and is adapted to be bent or curved upwardly upon itself into arcuate formation, thus providing an effecutal guard or shield for the outer side of the marking roller 7 and its marking teeth 8; the free end of this arcuate shield lying adjacent to the intermediate portion of the body 1 as 50 shown in the Figure 1.

In using the improved check marking device, the slip 2 is engaged with a pen, pencil or other device and when marking a check, is snugly engaged with the rearward side of 55 the same as shown in the Figure 1. At this time, the device is moved longitudinally over the check adjacent the value markings or indicating matter written or otherwise presented thereon and with such movement, the marking roller 7 will be caused to rotate in a clockwise direction, thus causing the series 60 of circumferentially disposed marking teeth 8 to successively enter the sheet 6, forming a plurality of absorbent projections upon the 65 face and reverse sides of the same adjacent

the value markings thereon, said projections having the outer portions thereof broken or torn free from the body of the instrument as well indicated by the numeral 12. By reason of the breaking or tearing of the outer portions of the projections 5 from the sheet 6, it will be understood that the fibers of the sheet will be ruptured and in consequence, that said free portions of the projections will be rendered absorbent. Hence, should attempts be made to fraudulently alter or raise a check subsequently to the original writing of the same and marking with the device, the ink or other writing fluid employed in such altering or raising operation will be absorbed by the free portions 12 of said projections and will present a blurred effect upon both sides of the check which may be readily noted or observed by a person examining the same. Should a person in attempting to fraudulently alter or raise a check marked with the device attempt to smooth out the projections upon the face of the instrument, such attempts will be readily obvious and in consequence, a person examining the instrument may readily detect the same. By reason of the mounting of the marking roller in the right angularly formed slots 4 in the supporting wings 3, it will be also understood that when the frame of the device is moved in a direction indicated by the arrow in the Figure 1, the extremities of the shaft 9 will be caused to remain in the lowermost lateral extremities of such slots and in consequence, the marking roller will be retained in its position within the opening 5 in order that the marking teeth 8 thereon will properly engage and mark the instrument 6 over which it is moved. However, should the device be moved in the opposite direction over the instrument 6, such movement will cause the extremities of the shaft 9 of the marking roller 7 to move out of the lateral extremities of the right angular slots 4 into the vertical portions thereof 100 and in consequence, the marking roller will be caused to move into the vertical portions of said slots to its innermost position, thereby preventing proper engagement with the check or sheet 6 in a manner to cause the forming of projections upon the face of the same. In this way, it will be readily understood that proper marking of a check with the device will at all times be ensured.

Manifestly, the construction shown is capable of considerable modification and such modification as is within the scope of my claims, I consider within the spirit of my invention.

I claim:

1. A check marking device comprising a frame, a roller supported thereon, and a plurality of teeth disposed about the periphery of said roller shaped to form series of projections upon both sides of a sheet engaged 130

thereby, the outer portions of which are broken away from the body of said sheet and thereby rendered absorbent.

2. A check marking device comprising a

5 frame, a roller rotatably supported thereon, and a plurality of circumferentially disposed series of teeth arranged about the peripheral surface of said roller shaped to form series of projections upon the sides of 10 a sheet engaged thereby, the outer portions of which projections are broken away from the body of said sheet and thereby rendered absorbent.

3. A check marking device comprising a 15 frame, a roller supported thereon, and a plurality of teeth disposed about the peripheral portion of said roller arranged at angles tangentially to the periphery of the roller and adapted to form series of projections upon 20 both sides of a sheet engaged thereby, the outer portions of which projections are broken away from the body of said sheet and thereby rendered absorbent.

4. A check marking device comprising a 25 frame, a roller supported thereon, and a plurality of triangularly shaped teeth disposed about the peripheral portion of said roller tangentially to the same and adapted to form series of projections upon both sides of a 30 sheet engaged thereby, the outer portions of which projections are broken away from the body of the sheet and thereby rendered absorbent.

5. A check marking device comprising a 35 frame, a roller rotatably mounted thereon, and a plurality of circumferentially disposed teeth on said roller adapted to enter a check at substantially right angles to the face thereof with rotation of the roller in one direction and to leave such check at angles more acute than those of their entrance.

6. A check marking device comprising a 45 frame, a roller rotatably mounted thereon, and a plurality of circumferentially disposed series of equi-spaced teeth on said roller adapted to enter a check at substantially right angles with relation to the face of the same with rotation of the roller in one direction and to leave such check at angles more 50 acute than those of their entrance with continued rotation of said roller.

7. A check marking device comprising a 55 frame, a roller movable horizontally and vertically in said frame and rotatable thereon, and a plurality of circumferentially disposed teeth on said roller adapted to enter a check at substantially right angles to the face thereof with rotation of the roller in one direction and to leave such check at angles more acute than those of its entrance with continued rotation of the roller.

8. A check marking device comprising a 60 frame, a roller rotatably mounted thereon, and a plurality of circumferentially disposed teeth on said roller adapted to enter a check

and form openings therein, the several sides of such openings being disposed in opposite directions with respect to the opposite sides of the check.

9. A check marking device comprising a 70 frame, a roller rotatably mounted thereon, and a plurality of circumferentially disposed teeth on said roller shaped to enter the check at substantially right angles with relation to the face thereof upon rotation of the roller 75 in one direction whereby to form openings in such check, certain of the sides of which are disposed in one direction and the remaining sides of which are disposed in an opposite direction.

10. A check marking device comprising a 80 frame having right angularly disposed supporting wings formed thereon provided with right angularly disposed bearing slots, a portion of said frame being cut away in 85 proximity to the supporting wings, a marking roller disposed transversely of the frame, a shaft passing through said roller having its opposite ends engaged in the right angular bearing slots, and a plurality of marking 90 teeth arranged upon the peripheral surface of said roller.

11. A check marking device comprising a 95 frame having an attaching slip formed on one end thereof, right angularly disposed supporting means carried upon the side portions of said frame and provided with right angularly formed bearing slots, a roller disposed transversely of the frame, a shaft passing through said frame having its extremities movably and rotatably mounted in the bearing slots, and marking teeth arranged about the peripheral surface of said roller.

12. A check marking device comprising a 100 frame, attaching means thereon, right angularly disposed supporting means upon certain of the side portions of said frame provided with right angularly formed bearing slots, a marking roller disposed transversely of the frame, a shaft passing through said roller having its opposite ends rotatably and slidably received in said right angular bearing slots, a portion of the frame adjacent the roller being cut away, and a 110 plurality of teeth disposed about the peripheral portion of said roller shaped to form series of projections upon both sides of a sheet engaged thereby, the outer portions of which projections are broken away from the body of said sheet and thereby rendered absorbent.

13. A check marking device comprising a 115 frame, attaching means thereon, right angularly disposed bearing wings upon portions of the opposite sides of said frame, that portion of the frame intermediate said wings being cut away, a transversely disposed roller adjacent said cut away portion of the frame, a shaft passing through said roller 120

125 and a plurality of teeth disposed about the peripheral portion of said roller shaped to form series of projections upon both sides of a sheet engaged thereby, the outer portions of which projections are broken away from the body of said sheet and thereby rendered absorbent.

having its opposite ends rotatably and slidably received in right angularly formed bearing slots in said supporting wings, and tangentially disposed right angularly shaped 5 marking teeth arranged about the peripheral surface of said roller adapted to form series of projections upon both sides of a sheet engaged thereby, the outer portions of which 10 projections are broken away from the body of said sheet and thereby rendered absorbent.

14. A check marking device comprising a frame having a resilient attaching clasp formed on one end thereof, right angularly 15 disposed wings upon portions of the opposite sides of the frame having right angularly formed bearing slots therein, that portion of the frame intermediate the supporting wings being cut away, a transversely disposed roller, a shaft passing through said 20 roller having its opposite ends rotatably and slidably mounted in said right angularly formed bearing slots, marking teeth arranged upon the peripheral portion of said roller, 25 and an extension formed upon the opposite end of said frame bent upwardly and

curved upon itself and arranged over the outer side of the marking roller and teeth thereon.

15. A check marking device comprising a 30 frame, an attaching clasp formed on one end of the frame, right angularly disposed supporting wings on portions of the opposite sides of said frame having right angularly formed bearing slots therein, that portion of 35 the frame intermediate said supporting frame being cut away, a transverse marking roller positioned adjacent the cut away portion of the frame, a shaft passing through said roller having its opposite ends rotatably and 40 slidably mounted in the right angularly formed bearing slots, a plurality of triangularly shaped marking teeth arranged upon the peripheral portion of said roller and disposed tangentially to the same, and 45 an extension on the opposite end of said frame curved upon itself and arranged over the outer side of the marking roller.

In witness whereof I have hereunto set my hand.

VINCENT CHELENA.
